HARNESS FOR CROSS WEAVING

John Jacob Kaufmann, Elkins Park, Pa., assignor
to Steel Heddle Manufacturing Company, Phil-
adelphia, Pa., a corporation of Pennsylvania

Application January 9, 1933, Serial No. 650,879

10 Claims. (Cl. 139—52)

My invention relates to metallic loom harness for use in that method of weaving known as "cross weaving", sometimes called "doup weaving" or "leno weaving" in which the warp threads are crossed or twisted about each other at as many points in the shed as may be desirable, either for a succession of picks, or according to a pattern or design to be produced.

This invention relates more particularly to the construction and formation of the guide or lifting heddles which are employed to raise the doup needles and thus cause each of the doup warps controlled thereby to be disposed on one side or the other of its ground warp as required.

The principal object of my invention is to provide a metal harness for cross weaving in which possibility of fouling of the warp threads will be eliminated, which will be simple, durable, and efficient for all types of cross weaving, which will be relatively inexpensive in construction, and which will be particularly useful for weaving the finer grades of cross woven fabrics.

With the foregoing object in view, my invention contemplates the provision of a doup needle, preferably punched from sheet metal, and a pair of lifting heddles of novel conformation for each doup needle, each of which heddles is made from a single strip of thin flat metal.

My present invention is particularly adaptable for use in connection with jacquard shedding mechanism, and insures the utmost freedom in the shedding of the warp, as well as serving to guide the warp during the shedding action so that the same will not be caught on the top of the doup needle or jammed between the needles and the lifting heddles and thus improperly raised.

The nature and characteristic features of my present invention will be more readily understood from the following description, taken in connection with the accompanying drawing forming part hereof, in which:

Figure 1 is an elevational view of one pair of heddles, and the associated parts, for controlling a pair of warp ends;

Fig. 2 is an enlarged detail view of the central portion thereof;

Fig. 3 is a side elevation of that portion of the structure shown in Fig. 2; and

Fig. 4 is a face view of a preferred form of doup needle employed in association with the lifting heddles for controlling the doup warp.

It will of course be understood that the description and drawing herein contained are illustrative merely, and that various changes and modifications may be made in the structure disclosed without departing from the spirit of the invention.

Referring to the drawing, in the particular embodiment of my invention therein shown, 10 is the doup needle, which is preferably made by

punching or stamping from a thin flat strip or sheet of metal. The doup needle 10 has at one end an eye portion 11, in which the eye 12 for the control of the doup warp 13 is located. The ground warp 14 extends freely between the pair of lifting heddles, and is controlled, in the event that it is desired to raise and lower the same, by separate harness (not shown). The outer margin 15 of the eye end 11 of the doup needle 10 is arched or curved, and the inner under margins 16 thereof are also curved, in gothic formation, meeting in a central apex.

Extending from the eye end 11 of the doup needle 10 are two legs 17, which terminate in enlarged portions 18, each of which is provided with a slot 19, for connection of the doup needle 10 with the needle lowering means, such for example as the lingo 20. As shown in the drawing, the slots 19 in the ends of the legs 17 of the doup needle 10 may be brought into register, and a single lingo 20 hooked through the openings in both legs.

There are provided two lifting heddles 21, each of which is formed from a single strip of thin flat metal. Each of the lifting heddles 21 has a straight upper portion 22, an intermediate inclined offset portion 23, and a straight lower portion 24, all preferably arranged with their faces in planes at right angles to the plane of the doup needle 10. Each of the lifting heddles 21 is also slotted, for the extension of the doup needle therethrough, the slot 25 being disposed in the inclined offset portion 23 and extending downwardly a short distance into the body of the lower straight portion 24.

Each of the shanks of the slotted portion of the lifting heddle 21 is slotted, and at the slotted portion one part 26 of each shank is bowed forwardly, and the other part 27 is bowed rearwardly, thereby to provide a guide and guard 40 which, when the heddle is in the lifting position with respect to the needle, extends over the eye end 11 of the doup needle and which prevents the ground warp 14 from becoming caught on the horizontal portion of said eye end of the doup needle. The guard which is thus provided by the bowed portions 26 and 27 of the shanks of the slotted portion of the lifting heddle 21 will also serve to prevent the warp ends which pass between adjacent sets of heddles from becoming lodged or caught on the eye end of the doup needle.

Each of the lifting heddles 21 may have a jacquard cord attached to the top end thereof, in the usual manner, and a lingo 28 may be hooked to the lower end of each of said lifting heddles.

By the provision of the slotted offset portion 23 of the lifting heddle 21, an appreciable space 29 will be obtained between the side margin of

the leg portion 17 of the doup needle 10 and the upper portion 22 of the lifting heddle 21 which remains in the lowered position, thus preventing the ground warp 14 from being gripped between 5 the doup needle 10 and the upper portion 22 of one of the lifting heddles when the other is raised, which would improperly raise the ground warp and cause a mispick.

By reason of the gothic formation of the inner margins 16 of the eye end 11 of the doup needle 10, said eye end will be properly centered with respect to the lifting heddle 21, and in this manner the bowed guide portions 26 and 27 will be so positioned with respect to the eye end of 15 the needle, as the lifting heddle is raised, as to guide any of the warp ends which would tend to lodge on the top of the needle to such position that the same will readily slide down the side of the needle.

20 Furthermore, cross weaving harness constructed as aforesaid will be quite free in its action, so that there will be no likelihood of the doup needle remaining in the elevated position when the lifting heddle is lowered, nor will there be 25 any likelihood of the lifting heddles themselves being improperly held in an elevated position by reason of any jamming with respect to the doup needle.

It will therefore be seen that there is provided 30 a cross weaving harness which may be controlled by shaft harness frames but which, however, is particularly adaptable for jacquard control, in that the weight of the lingoes will at all times be sufficient to return the parts properly to their 35 lowered positions.

I claim:

1. In harness for cross weaving, a lifting heddle made of a single flat strip of metal having a portion slotted for the extension of the doup needle 40 therethrough, and having a guard adjacent the slotted portion extending beyond the medial line of the doup needle to guide the warp over the top of the doup needle, when the heddle is in the lifting position with respect to the doup needle.

45 2. In harness for cross weaving, a lifting heddle made of a single flat strip of metal having a portion slotted for the extension of the doup needle therethrough, and each of the shanks of the slotted portion having one part extending forwardly 50 and another part extending rearwardly, thereby to provide a guard to guide the warp over the top of the doup needle.

55 3. In harness for cross weaving, a lifting heddle made of a single flat strip of metal having a portion slotted for the extension of the doup needle therethrough, and each of the shanks of the slotted portion being slitted, one part of said slitted portion of each shank being bowed forwardly and the other part thereof being bowed 60 rearwardly, thereby to provide a guard to guide the warp over the top of the doup needle.

65 4. In harness for cross weaving, a lifting heddle made of a single flat strip of metal having an upper straight portion, an intermediate inclined offset portion, and a lower straight portion, the offset portion being slotted for the extension of the doup needle therethrough, and each of the shanks of the slotted portion being slitted, one 70 part of said slitted portion of each shank being bowed forwardly and the other part thereof being bowed rearwardly, thereby to provide a guard to guide the warp over the top of the doup needle.

75 5. In harness for cross weaving, a doup needle having an eye through which the doup warp ex-

tends, said needle being made of thin flat metal, a pair of lifting heddles each made of a single flat strip of metal having an upper straight portion, an intermediate inclined offset portion, and a lower straight portion, all arranged with their faces lying in planes at right angles to the plane of the doup needle, and the offset portion being slotted for the extension of the doup needle therethrough.

6. In harness for cross weaving, a doup needle 10 having an eye through which the doup warp extends, a pair of lifting heddles each made of a single flat strip of metal having a portion slotted for the extension of the doup needle therethrough, and having a guard adjacent the slotted portion extending beyond the medial line of the doup needle to guide the warp over the top of the doup needle when the heddle is in the lifting position with respect to the doup needle.

7. In harness for cross weaving, a doup needle 20 having an eye through which the doup warp extends, a pair of lifting heddles each made of a single flat strip of metal having a portion slotted for the extension of the doup needle therethrough, and each of the shanks of the slotted 25 portion having one part extending forwardly and another part extending rearwardly, thereby to provide a guard to guide the warp over the top of the doup needle.

8. In harness for cross weaving, a doup needle 30 having an eye through which the doup warp extends, a pair of lifting heddles each made of a single flat strip of metal having a portion slotted for the extension of the doup needle therethrough, and each of the shanks of the slotted 35 portion being slitted, one part of said slitted portion of each shank being bowed forwardly and the other part thereof being bowed rearwardly, thereby to provide a guard to guide the warp over the top of the doup needle.

9. In harness for cross weaving, a doup needle having an eye through which the doup warp extends, a pair of lifting heddles each made of a single flat strip of metal having an upper straight portion, an intermediate inclined offset portion, 45 and a lower straight portion, all lying in planes at right angles to the plane of the doup needle, the offset portion being slotted for the extension of the doup needle therethrough, and each of the shanks of the slotted portion being slitted, one 50 part of said slitted portion of each shank being bowed forwardly and the other part thereof being bowed rearwardly, thereby to provide a guard to guide the warp over the top of the doup needle.

10. In harness for cross weaving, a doup needle 55 having an eye through which the doup warp extends, said needle being made of thin flat metal, a pair of lifting heddles each made of a single flat strip of metal having an upper straight portion, an intermediate inclined offset portion, and a lower straight portion, all lying in planes at right angles to the plane of the doup needle, the offset portion being slotted for the extension of the doup needle therethrough, and each of the shanks of the slotted portion being slitted, one 60 part of said slitted portion of each shank being bowed forwardly and the other part thereof being bowed rearwardly, thereby to provide a guard to guide the warp over the top of the doup needle, and the inner margins of the eye portion of the 65 needle being curved and extending to a central apex thereby to center the eye portion of the needle with respect to the guard when the lifting heddle is raised.
